UNITED STATES PATENT OFFICE.

AMOS G. FITZ, OF AUBURN, MAINE.

LAST.

No. 882,556

Specification of Letters Patent. Patented March 24, 1908.

Application filed June 6, 1907. Serial No. 377,534.

To all whom it may concern:

Be it known that I, AMOS G. FITZ, a citizen of the United States, residing at Auburn, in the county of Androscoggin and State of Maine, have invented new and useful Improvements in Lasts, of which the following is a specification.

My invention relates to improvements in lasts.

10 Lasts used in connection with modern shoe machinery must be very firm to withstand the strain upon them. In some of the processes through which they pass in the manufacture of shoes, great pressure is exerted upon them, especially during the time they are supported on the jack or spindle. The tendency of these lasts when subjected to these strains is to split on horizontal lines of cleavage midway the top and bottom in line with the grain of the last and more particularly at a point at or near where the spindle impinges the thimble, truss or wood of the last, as the case may be. Various means have been employed to resist this 15 splitting tendency as for example, transverse trusses extending through the last from side to side at a point adjacent the bottom of the spindle. These do not however accomplish the desired purpose. The strain even then comes all in substantially the same 20 plane which is the plane of the truss.

My invention is designed to overcome this objection and consists in forming the spindle hole with lateral recesses and mounting 25 therein U-shaped trusses, the vertical parts of which lie in said recesses, the bottom extending transversely across the spindle hole and the ends anchored in the last in such a way that the strain of the spindle on the 30 truss is supported at the top of the last instead of midway the top.

I have illustrated in the drawings some of the many forms in which my invention may be embodied.

45 In the drawings herewith accompanying and making part of this application, Figure 1 is a transverse sectional view of a last taken through the spindle hole and showing one form of my improved spindle support mounted therein; Fig. 2 is a similar view showing a 50 different form; Fig. 3 is a side elevation partly in section showing still another form of my invention; Fig. 4 is a transverse vertical sectional view taken through the spindle hole showing still another embodiment of my improvement and Fig. 5 is a horizontal

section of a portion of a last showing the lateral recesses in the spindle hole and the position of the truss therein.

Same letters of reference refer to like parts.

In said drawings A represents the last, B the usual spindle hole. Mounted in the spindle hole is a U-shaped truss, a portion C extending across the bottom of the truss, the vertical portions D extending upwardly and lying in recesses E in the spindle hole and the ends F anchored in the last.

In Fig. 1 the ends of the truss are shown turned over and taking into the top of the last, as seen at G. In Fig. 2 the ends of the truss extend down the outsides of the last and are turned upwardly taking into the bottom, as seen at H. In Fig. 3 the ends of the truss are turned to form eyelets near the top 75 of the last, as seen at I, and are further supported by pins J passing transversely through the last and through said eyelets. In Fig. 4 the ends are turned down to an acute angle with the sides, as seen at K, and are caused to take into diagonally extending holes L in the sides of the spindle hole. In this case the holes may be below the top of the last as shown and when so constructed the truss is inserted in the spindle hole by 80 pressing the upper ends together until they clear the upper end of the last, when they pass readily into the diagonal holes expanding as they enter. The truss may be used with or without a thimble M. In Figs. 1 and 90 3, thimbles are shown, while in Figs. 2 and 4, no thimble is shown. When a thimble is used it may or may not have a bottom. When the thimble has a bottom the spindle rests on the bottom of the thimble which in 95 turns rests upon the truss. When the thimble is bottomless the spindle rests directly on the portion of the truss extending transversely across the spindle hole, as seen in Fig. 1. The truss may rest directly upon 100 the bottom of the spindle hole as shown in Fig. 1, or it may be spaced apart from the bottom as seen in Fig. 2. It is noted that the sides of the truss are flush with the walls of the spindle hole. It is also noted that the 105 portions of the truss shown in Fig. 2 which pass down on the outside of the last are countersunk, so as to be flush with the sides of the last.

Having thus described my invention and its use I claim:

1. The combination with a last having a

spindle hole and vertical truss-receiving recesses therein, of a truss extending across the bottom of said hole, its sides extending upwardly and positioned in said recesses and 5 its ends anchored in the last.

2. The combination with a last having a spindle hole and vertical truss-receiving recesses therein, of a truss extending across the bottom of said hole, its sides extending upwardly and positioned in said recesses and 10 its ends anchored in the last near the top thereof.

3. The combination with a last having a spindle hole, vertical truss-receiving holes

and diverging anchor holes therein, of a 15 truss extending across the bottom of said spindle hole, its sides positioned in said recesses and its ends bent to conform to said anchor holes.

In testimony whereof I have signed my 20 name to this specification in presence of two subscribing witnesses this fourth day of June, A. D. 1907.

AMOS G. FITZ.

In presence of

JOHN A. MORRILL,
DAISY E. YOUNG.
